Specification for Design.

Patented June 6, 1916.

Application filed January 10, 1916. Serial No. 71,359. Term of patent 7 years.

To all whom it may concern:

Be it known that I, SAMUEL KAUFFMAN, a citizen of the United States, residing at St. Louis, Missouri, have invented a new, original, and ornamental Design for a Radiator-Shield, of which the following is a specification, reference being had to the accompanying drawing, forming a part thereof.

The drawings illustrate a radiator shield made in accordance with my new design and in said drawings Figure 1 is a perspec-

tive view. Fig. 2 is a front elevation. Fig. 3 is a side elevation of the radiator shield.

I claim:

The ornamental design for a radiator shield, as shown.

In testimony whereof, I have hereunto set my hand this 11th day of August, 1915.

SAMUEL KAUFFMAN.
